UNITED STATES PATENT OFFICE.

ALLEN H. KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

CAST-OFF BUCKLE.

Application filed June 8, 1928. Serial No. 114,411.

This invention relates to buckles and has special reference to a buckle of the type known as a "cast-off buckle," this buckle being peculiarly adapted for use as a belt buckle, a vest buckle, suspender buckle, hat band buckle, book strap buckle, and in fact, for all the purposes to which a buckle may be applied.

One important object of the invention is to provide an improved general construction of buckle of this type.

A second important object of the invention is to provide an improved "cast-off buckle" constructed in such manner that neither belt end engaged with the buckle can slip, the arrangement being such that the greater the stress on the belt the more tightly will the belt ends be gripped by the buckle.

20 A third important object of the invention is to provide an improved and simplified buckle of this character wherein the parts may all be made from stamped sheet metal.

25 A fourth important object of the invention is to provide a device of this character wherein the parts may be assembled in a simple manner without riveting or the like and in which the assembled parts can be separated only by the use of excessive force.

30 A fifth important object of the invention is to provide a device of this character which will not mar or damage the texture of the webbing or fabric to which it is attached.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a face view of the improved buckle showing a pair of strap or ribbon ends connected thereto.

Figure 2 is a section on the line 2—2 of Figure 1.

Figure 3 is a rear view of the buckle with the strap or ribbon omitted, one flange of the body being partly broken away.

Figure 4 is a section on the line 4—4 of Figure 3.

Figure 5 is a front view of one of the sliding grip bars used herewith removed 55 from the remainder of the buckle.

The body of the invention may be of any desired shape and may also be provided with such ornamentation as will be suitable for the use to which the buckle is to be put. 60

This body 10 is provided with a pair of spaced slots 11 each having at least one edge 12 suitably shaped to assist in gripping the strap or ribbon S. As here shown the edge 12 is straight and such a straight edge is 65 desirable in cases where the buckle is used on soft or finely finished straps such as hat bands and fine leather belts. In other cases such as for trunk straps and the like some form of serration may be used, but it is not 70 deemed necessary to illustrate such modifications as they are well known to those skilled in the art. At each side of the buckle and projecting rearwardly from the body in confronting relation is a pair of angle flanges 13 which form with the body a pair of guide grooves for the ends of the gripping bars. Each gripping bar has a central portion 14 which is preferably ar- 75 cuate in cross section and at each end of this central portion the bar has a flat head 15 fitting in a respective groove of the body. These heads are offset rearwardly of the central portion so that the latter lies in a 80 respective slot 11. By this arrangement the bars are prevented from becoming detached 85 from the body although they slide freely toward and from the edges 12.

Preferably, the body is stamped from a single piece of sheet metal with the opposite 90 edge turned rearwardly and then toward each other to form the angle flanges and provide the grooves for the heads 15. Also, the gripping bars likewise preferably stamped from sheet metal, the shape of the central 95 portions of these bars not only adding stiffness to the bar but also coacting with the edges 12 to produce a secure grip on the strap or ribbon, and due to the formation of the bars a smooth bite is effected between 100 the head and strap during engagement which will not mar or damage the texture of the strap.

In use each strap is passed from rear to 105 front of the body 10 through a respective 105 slot 11 between the edge 12 and the adjacent

gripping bar. The strap end is then passed from front to rear of the body through the same slot 11 but on the opposite side of the gripping bar. When thus arranged any pull 5 on the strap S away from the buckle carries the gripping bar towards the edge 12 in the direction of such pull so that the material of the strap is tightly gripped between the bar and said edge and the greater the 10 stress on the strap the greater will be the clamping effect. Obviously the strap may be adjusted or released by moving the gripping bar away from the coacting edge 12.

There has thus been provided a simple 15 and efficient device of the kind described and for the purpose specified.

It is obvious that minor changes may be made in the form and construction of the invention without departing from the material spirit thereof. It is not, therefore, desired to confine the invention to the exact 20 form herein shown and described, but it is

desired to include all such as properly come within the scope claimed.

Having thus described the invention, what 25 is claimed as new, is:

A buckle comprising a frame having an opening and provided with grooves located beyond the ends of the opening and disposed transversely thereof and a bar having an intermediate straight portion curved 30 transversely and disposed in the opening of the frame, said bar having its ends offset with relation to the intermediate portion and forming heads lying in the grooves of the 35 frame, said heads lying in a plane at one side of the edge of the intermediate portion of the bar, said heads having side portions disposed beyond the side edges of the intermediate portion of the bar, and the edges 40 of the side portions of the heads being rounded.

In testimony whereof I affix my signature.

ALLEN H. KERNGOOD.
